US00D831061S

(12) **United States Design Patent** (10) Patent No.: **US D831,061 S**
(45) Date of Patent: **** Oct. 16, 2018**

(54) **DISPLAY PANEL WITH GRAPHICAL USER INTERFACE**

(71) Applicants: **Kyung Hee Yoon**, Seongnam-si (KR);
Hyun Ah Hwang, Seongnam-si (KR);
Jae Ho Song, Seongnam-si (KR);
Seung Eun Lee, Seongnam-si (KR)

(72) Inventors: **Kyung Hee Yoon**, Seongnam-si (KR);
Hyun Ah Hwang, Seongnam-si (KR);
Jae Ho Song, Seongnam-si (KR);
Seung Eun Lee, Seongnam-si (KR)

(73) Assignee: **NAVER CORPORATION**,
Gyeonggi-Do (KR)

(**) Term: **15 Years**

(21) Appl. No.: **29/548,565**

(22) Filed: **Dec. 15, 2015**

(30) **Foreign Application Priority Data**

Oct. 8, 2015 (KR) 30-2015-0050907

(51) LOC (11) Cl. **14-04**

(52) U.S. Cl.

USPC **D14/487**; D14/495

(58) **Field of Classification Search**

USPC D14/485-95; D18/24-33; D19/6, 52;
D20/11; D21/324-33; 715/700-867,
